1 Claim

ABSTRACT OF THE DISCLOSURE

A terminal connector for an electrical conductor comprising a pair of eye members joined by a bendable strip to facilitate bending one eye member over onto the other with the hook or circle end of an electrical conductor therebetween.

BACKGROUND OF THE INVENTION

Field of invention

The invention relates to a terminal conductor for electrical conductors and particularly to a conductor for isolating the binding screw which secures the terminal conductor in place from the conductor to prevent electrolysis.

Description of the prior art

Prior art terminal connectors have either required the use of dies or complex tools for bending or forming the connector in clamping relationship to an electrical conductor, or have comprised several or more separate parts which can become separated or have not been effective to isolate the binding screw from the conductor. Prior art located during a search is as follows: 451,364, Brewer; 1,204,935, Busby; 2,442,767, Gookin; 2,643,366, Berg; 2,648,054, Berg; and 2,748,368, Gookin.

SUMMARY

The connector of the present invention overcomes the above disadvantages by being formed of one piece comprising a pair of eye members connected by a bendable strip to facilitate bending the connector at a midpoint to enable the eye members to assume an opposed relationship with a bare conductor end therebetween, the connector having integral bendable clamping means for clamping the eye members together and one of the eye members having a flange to isolate the conductor end from a binding screw, and the clamping means being capable of acting as a lock washer when the connector is secured in place.

DESCRIPTION OF THE DRAWINGS

FIG. 1 is a plan view of a connector of my invention, showing in broken lines the end portion of an electrical conductor bent to lie in the clamping end of the connector;

FIG. 2 is a side elevational view of the connector of FIG. 1;

FIG. 3 is a plan view of the connector after the cover end has been bent over to overlie the clamping end;

FIG. 4 is a side elevational view of the bent connector of FIG. 3;

FIG. 5 is a view like FIG. 3, but showing the clamping fingers bent in clamping relation to the cover end;

FIG. 6 is a side elevational view of a connector in its FIG. 5 condition;

FIG. 7 is a midsectional view of the connector in its operative position on a terminal block; and

FIG. 8 is a midsectional view like FIG. 7, but taken 90° from the FIG. 7 view.

Referring to FIGS. 1 and 2, the connector comprises two spaced eye members 11 and 13 joined by an integral bendable connecting strip 15. Eye member 11 has a cen-

2

tral hole 17 defined by an upstanding circular flange 19, the outer margin of said member being bent upwardly to form a retaining flange 21 including a curved portion concentric with flange 19. The retaining flange 21 has upwardly extending bendable clamping fingers 23.

Eye member 13 may be considered as a cover member having a central hole 27 of a size slightly larger than the external diameter of flange 19. The outer margin of eye member 13 is bent up to form a flange 29, part of which is concentric with hole 27.

FIG. 1 shows the bare end portion 31 of an insulated stranded electrical conductor 33 bent into hook form and placed in the eye member 11 in nesting relation in the curved trough provided by flanges 19 and 21, it being understood that conductor 33 is bent downwardly to extend below the cover member 13 as the parts are shown in FIG. 1.

Now, the cover member 13 is forced over to overlie the clamping member 11, in the process bending the connecting strip 15 so that the connector is now in the form shown in FIGS. 3 and 4. In this condition of the connector, the hole 27 may surround the circular flange 19 or directly overlie the same, depending on the size of the conductor 33.

Next, the fingers 23 are bent downwardly as shown in FIG. 5 firmly against the cover member 13 with sufficient pressure to force the flange 19 upwardly near or into the hole 27. This action may compress the stranded wire until it is rather elliptical in cross section (as shown in FIG. 7). The connector is now in the form shown in FIGS. 5 and 6.

Now, the connector is inverted as shown in FIG. 7 to locate the fingers 23 lowermost, and the connector then secured in place by a terminal screw 41 which passes through the hole 17 in the connector and threads into the terminal block 43 or other suitable member. As the screw 41 is tightened, it will further compress the connector to force the flange 19 into the opening 27 whereby the screw 41 is separated by a wall from the stranded conductor 33 so that electrolysis cannot occur in the event the screw and conductor are of such dissimilar metals that electrolysis would occur.

It is pointed out that with the fingers 23 lowermost, these fingers act as a lock washer for holding the connector in place the same as if a separate lock washer had been utilized.

While the invention has been shown in connection with a stranded conductor, it is equally useful for mounting on the end of a solid conductor.

It is pointed out that the tip ends of the fingers 23 preferably are rounded somewhat so that they are not sharp and can themselves be readily bent over by finger contact and without aid of tools, although if pliers are handy, they may be used in bending the fingers down. Thus, with a simple screwdriver and perhaps a pair of pliers, a connector of my invention may be used to mount on the ends of a conductor, and the conductor mounted in place without the use of any other tools.

It is pointed out that when the connector is turned over or inverted in its FIG. 7 position, the wire 33 extends in the same direction as the screw is turned, as is common practice in the electrical industry.

It is further pointed out that the binding screw or terminal screw 41 functions to clamp the bent fingers or prongs 23 against the under surface of the terminal block or plate so that the prongs have firm engagement with such plate and can function in lock washer fashion.

An important advantage of the connector is that once the conductor is properly contained within the connector, the conductor is totally isolated from the binding screw. This prevents electrolysis occurring between the conductor and the binding screw. If desired, the connec-

tor could be made of aluminum coated with tin (or perhaps cadmium or silver) so as to prevent electrolysis between, say, a brass or copper binding screw and the wire, which may for instance be made of aluminum. The connector can be made in many sizes. For instance, one connector could be made of a size to handle 8 to 10 gauge conductors, another 12 to 14 gauge conductors, and another 16 to 18 gauge conductors. This is merely exemplary and not binding on the forms the connector can assume.

It may be desirable to make the recesses between the teeth or prongs or fingers 23 rounded at the bottom to avoid stress concentration or fractures which might otherwise develop in the eye member 11.

One manner of forming the connectors of my invention is to provide a strip in coil form and feed it from the coil where identification numbers can be stamped into one side of the strip. At a subsequent stage, two holes will be punched through the strip and at the next stage the severing guide will come down and sever out the form 20 of the blank, including the formation of the prongs or fingers 23 which of course will still be flat at that time. The thus formed blank will then be fed through a subsequent stage where dies will form the flanges 19, 29, and 21 and bend up the fingers of prongs 23, as shown in FIGS. 1 and 2.

While the connector is ideally suited for handling aluminum wire to prevent electrolysis between the aluminum wire and brass or copper screw, the connector of course can be used with wire of any material, and the invention is obviously not limited to use with aluminum wire or stranded wire.

For marine use, the connector could be made of copper, bronze or brass and then could be plated with either cadmium, silver or tin whereby to act as an electrolysis barrier between a conductor and a binding or terminal screw.

The preferred embodiment of the invention has been described above, but it will be appreciated that the connector may assume other forms.

I claim:

1. A terminal connector for an electrical conductor consisting of a single piece of metal which comprises a pair of eye members spaced from one another and connected by a bendable connecting strip which can be bent

to enable said eye members to be disposed in facing relationship to one another,

one eye member having an upstanding outer flange projecting from peripheral edge portions of said one eye member, said flange being of generally semicircular form and facing in the direction of the other eye member and generally defining a cup having an open side, said other eye member being of smaller size than the interior of said cup to enable said other eye member to fit in nesting relationship within said cup when said strip is bent to dispose said eye members in facing relationship to one another, the open side of said cup accommodating said strip and said other eye member in the facing relationship of said eye members, said flange having upstanding bendable fingers which can be bent inwardly to overlie said other eye member and retain it in place in the operative condition of said conductor, said one eye member having an upstanding inner flange defining a circular rim, the hole in said other eye member being larger than said rim to enable said rim to pass into said hole in a facing relationship of said eye members, said other eye member having a semicircular upstanding flange projecting from peripheral edge portions of said other eye member and adapted to fit in embracing relationship to the end of a conductor clamped in said connector.
